UNITED STATES PATENT OFFICE

WILLIAM H. WINTERS, OF DULUTH, MINNESOTA

PENCIL SHARPENER

Application filed June 16, 1926. Serial No. 116,417.

It is the purpose of the present invention to provide, in a pencil sharpener, a construction and arrangement of elements which are automatic in their operations as a result of forcing the pencil to be sharpened downwardly between the cutting members.

Another purpose is the provision of a spiral threaded shaft to engage with opposed teeth whereby rotary motion may be imparted to the shaft which, in turn, imparts movement to spiral pencil cutters on the downward stroke of the shaft, said cutters being carried by a frame under tension of tensioning means to return the frame to initial position without imparting movement to the cutters.

Still another purpose is the provision of a tapered receiver for the reception of the end of a pencil for holding the latter in position, whereby the cutters may remove a uniform surface from the end of the pencil.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a vertical sectional view of a pencil sharpener constructed in accordance with the invention.

Figure 2 is a plan view.

Figure 3 is an elevational view broken away at the upper end to present a section at right angles to that of Figure 1.

Figure 4 is a transverse sectional view on line 4—4 of Figure 1.

Figure 5 is a transverse sectional view on line 5—5 of Figure 1.

Figure 6 is a sectional view of the upper end of the shaft 5.

Referring to the drawings, 1 is a casing which comprises a base 2 and a contracted upper end portion 3. Rising from the bottom of the base is a tubular shell 4 for the reception of a shaft 5 which has an exterior spiral thread 6. Fixed in any suitable man-

ner upon the upper end of the tubular shell is a cap 7 provided with an opening 8 through which the shaft 5 operates.

The opening 8 has diametrically opposite, lugs or teeth 9 which engage with the spiral threads on the shaft 5, thereby adapted to cause revoluble movements to be imparted to the shaft upon depressing the same into the tubular shell 4. Where the contracted end portion 3 projects from the base 2, inwardly extending supports 10 are provided for the support of the rods 11, the upper ends of which are mounted in bearings 12 of the arcuate top wall 13 of the contracted end portion 3. The top wall 13 has a central opening 14 through which the end of the pencil to be sharpened passes.

Mounted for up and down movement upon the rods 11 is a ring gear 15, the inner margin of which has gear teeth 16, and depending from the ring gear are diametrically opposite arms 17 to the lower ends of which a ring plate 18 is integrally connected. A base 19 with its upper face 20 gradually diverging outwardly and downwardly is supported on the ring plate 18. A stud 21 has its tapered head 22 fixed in any suitable manner in the base 19, so as to rotate with the latter. The stud has its lower end swiveled at 23 in the upper end of the shaft 5.

While the stud is swiveled in the shaft 5, it also has a slight axial movement relative to the shaft. The upper end of the shaft has ratchet teeth 24 which are engaged by the ratchet teeth 25 on a shouldered part of the under face of the base 19. Upon applying pressure on the base 19, causing the ratchet teeth 25 to engage with the teeth 24, the base and the shaft 5 will rotate together upon downward movement of the shaft, and upon upward movement of the shaft, due to the slight axial play of the stud in the shaft 5, the ratchet teeth will separate, thereby permitting the base to remain idle while the shaft rotates.

A cap 26 is mounted concentric with the ring gear 15 and is fastened thereto, and journaled in bearings of the cap and the base 19 are the pintles of the cutting rolls or cylinders 27 which have spiral cutting threads 100

28. The cutters which are in the form of cylinders have their upper ends provided with gears 29 which mesh with diametrically opposite portions of the ring gear.

5 Since the shaft 5 and the base 19 rotate upon downward movement of the shaft, the cutters swing around the end of the pencil and due to their gear connections 29 with the ring gear, the gears themselves rotate, thereby causing the cutting threads of the cutters to remove uniform surfaces from the pencil until the end of the pencil is sharpened. Upon imparting a downward movement to the shaft 5, the shaft will make at least three 10 revolutions while the cutters themselves will receive at least twelve revolutions which, it is believed, will remove sufficient surface from the end of the pencil to give the pencil a sharpened tapering point. The sharpened 15 end of the pencil is tapered due to the fact that the cutters 27 diverge upwardly from each other, their lower end faces being parallel with the conical face of the base 19.

A support 30 with a tapered bore depends 20 from the cap 26 with the bore concentric with an opening 31 in the cap. This support with its bore constitutes means to receive the end of the pencil when applied between the cutters, thereby holding the pencil firmly; 25 whereby uniform shavings may be removed from the end of the pencil by the cutters during their revoluble movements.

Suitable springs 32 are in surrounding 30 relation to the rods 11 and are interposed between the supports 10 and the ring gear 15, thereby acting to return the frame to its raised position after having been depressed.

In the operation, a pencil to be sharpened 40 may be inserted through the opening of the top 13 and through the opening of the cap 26 so that the end of the pencil will enter the tapered bore of the support 30. Pressure is applied upon the pencil sufficiently to cause the shaft 5 to move axially into the tubular 45 shell, and due to the teeth or lugs 9 engaging the spiral thread of the shaft, the shaft receives revoluble movement as well as the base 19. Due to the base rotating, the cutters swing around the surface of the pencil 50 and due to this movement and their gear connections with the ring gear, the cutters themselves rotate upon their diverging axis so that the spiral cutting thread of the cutters 55 may remove a uniform surface from the end of the pencil.

Upon relieving pressure upon the pencil and the shaft 5, the springs 32 will expand 60 (having been contracted during the depressing movement of the shaft and pencil), thereby raising the ring gear and its frame to its normal position. The cutters in returning to their initial positions do not rotate, due to a separation of the ratchet 65 teeth 24 and 25.

The invention having been set forth, what is claimed is:

1. A pencil sharpener comprising a casing, a frame mounted therein and spring supported in a raised position, a cutter supporting base carried by the frame, means for revolving the base upon downward movement of the frame, divergent cutters carried by the base, and means for imparting axial rotation to the cutters when the base is revolved, the base revolving means having operative connections with the base to couple it to the latter upon downward movement of the frame but to release it from the base upon upward movement of the frame.

2. In a pencil sharpener, a casing provided with a tubular guide, a spring supported frame mounted normally in a raised position in the casing, a base revolvably supported in the frame and provided with diverging cutters, a shaft with spiral threads operatively engaging with the tubular guide, whereby it may receive revoluble movement upon depressing the shaft, ratchet means connecting the base and the shaft whereby the base may rotate with the shaft upon downward movement of the latter and remain idle upon upward movement thereof, and means for imparting revoluble movement to the cutters themselves.

3. In a pencil sharpener, a casing provided with a tubular guide, a spring supported frame mounted normally in a raised position in the casing, a base revolvably supported in the frame and provided with diverging cutters, a shaft with spiral threads operatively engaging with the tubular guide, whereby it may receive revoluble movement upon depressing the shaft, ratchet means connecting the base and the shaft whereby the base may rotate with the shaft upon downward movement of the latter and remain idle upon upward movement thereof, means for imparting revoluble movement to the cutters themselves, said ratchet means comprising a stud fixed to and in a depending position from the base and provided with a swiveled slide connection with the shaft, and engaging and disengaging ratchet teeth on the end of the shaft and the base, whereby the base may rotate with the shaft upon its downward movement and remain idle upon its upward movement.

In testimony whereof he affixes his signature.

WILLIAM H. WINTERS.
